UNITED STATES PATENT OFFICE.

FRANCIS WILLIAM HEWS, OF MANOR PARK, ENGLAND.

MACHINE FOR CASTING TYPE.

No. 799,054.

Specification of Letters Patent.

Patented Sept. 12, 1905.

Application filed July 5, 1904. Serial No. 215,450.

To all whom it may concern:

Be it known that I, FRANCIS WILLIAM HEWS, a subject of the King of Great Britain, residing at 88 Browning road, Manor Park, in the county of Essex, England, have invented new and useful Improvements in Machines for Casting Types, (for which I have applied for a patent in Great Britain, No. 16,068, bearing date the 21st of July, 1903,) of which the following is a specification.

The object of this invention is to so construct the molds wherein to cast the types and to so arrange mechanism to open and close said molds that any convenient number of types of the same or various sizes and sorts may be cast simultaneously at one operation of the machine; and a further object of this invention is to use mechanism whereby types so cast may have their tailings removed and the types so finished may be automatically collected side by side and close together ready to be placed on the type-founder's stick for assortment, to attain which I arrange my improved molds and mechanism for opening and closing same and mechanism for cutting off the tailings and for delivering and collecting the types, substantially as described, by the aid of the accompanying drawings, in which—

Figure 1 is an end elevation of my machine, showing the principal mechanical parts therein in position when the cast types are being delivered from the molds, and Fig. 2 is a front elevation of the same. Fig. 3 is a front view of my improved molds when closed and part of the mechanism for operating the same, and Fig. 4 is a similar view when the molds are open. Fig. 5 is a longitudinal sectional elevation of the type-collecting table at the front of my machine, and Fig. 6 is a plan of same. Fig. 7 is a plan of a type-holder, and Fig. 8 a cross-section of same. Fig. 9 is a side view of the complete machine; and Fig. 10 is a side elevation of the machine upon a reduced scale, illustrating the mechanism for causing the shaft K to rock and for operating the trimming-knife J.

Similar letters and numerals of reference denote corresponding parts in each view.

My improved molds within which are cast the types are made out of hardened-steel blocks in the following manner: The upper part of each said mold consists of the top and

one side marked m' of the mold M, and the bottom and opposite side marked m^2 forms 55 the other part of said mold when closed, as shown at Fig. 3. The parts m' of the respective molds M are secured to an upper carrier A, which is fixed to side arms B, carried on a cross-shaft b' , which is supported on bearings, 60 (not shown,) but fixed to bed-plate b^2 of the machine. The lower parts m^2 of the respective molds M are fixed to a lower carrier C.

The upper carrier A may carry any desired number of parts m' , corresponding to the number of molds M required, and combined they remain a fixture to the side arms B, which latter simply rock or reciprocate. The bottom carrier C, with its respective mold parts m^2 , however, receives a lifting and lowering 70 motion by being carried on the top of two rods R, which have inclined or angular sliding parts S bearing in inclined or angular slides or bosses s' , which are made with the frame part s^2 of my machine. The rods R 75 may be forced upward and downward by means of cams r' (see Figs. 1 and 9) or in any other well-known way, and such mechanism may receive its motion from the shaft W by means of a chain-gear v' , and the arms B may 80 receive a to-and-fro motion by means of a cam Q working on the driving-shaft W, carried in the frame s^2 of the machine, and being pulled back by a spring q' .

At the top of each arm B, I fix a plate or 85 bracket b^4 , (shown in dotted lines, Fig. 1,) which carries a rod b^5 , extending from one bracket to the other. At the front of the upper carrier A, I hinge, swivel, or pivot a number of matrix-bars D, and to the rod b^5 I 90 fix or mount a corresponding number of levers E, the lower end of each of which comes in contact with the upper front part d' of its respective matrix-bar D. The brackets b^4 also carry a shaft f' , extending from bracket to bracket at 95 a lower level than the rod b^5 , and this shaft f' carries a number of levers F corresponding to the number of matrix-bars D and so arranged that at times the ends of adjustable screws f^2 , which are carried through the lower parts of 100 said levers F, come in contact with the lower parts of the matrix-bars D. The top part of each lever F is formed with a projection f^3 . The brackets b^4 also carry a shaft K, which extends from one bracket to the other, and it 105 has secured to it a continuous tappet k' , which

extends between the parts f^3 of levers F and the face of levers E. The shaft K is caused to rock by a lever 10, worked by a connecting-rod 11, coupled to a rod 12, which latter has a runner 13 bearing in a fixed quadrant 14. (See Fig. 10.) As the arms B travel to position for closing the molds M the runner 13 lifts the rod 12, and the connecting-rod 11 lifts the lever 10, so causing the tappet k' to press 5 against the respective ends f' of the levers F, and when the arms B are in the position shown at Fig. 1 the tappets k' press back the levers E, which press the top part d' of the matrix-bars D, and so cause the lower ends 10 of said bars to extend away from the upper parts m' of the molds M. Each matrix-bar 15 D has a matrix d^2 formed on its inner face, and when the arms B move to position so as to bring the parts m' over the parts m^2 close 20 up thereto, as shown at Fig. 3, the matrix-bars D are caused to close by the reverse action of the tappets k' coming in contact with the projections f^3 and causing the protruding inner ends of the screws f^2 to press against the 25 bars D at the same time the levers E are released, so that each matrix d^2 takes up its required position at the end of each mold M, and the same are then ready for an injection 30 of molten metal, which is forced through the respective nozzles Z from a melting-pot V by means of pistons and cylinders or pumps in a well-known manner—that is to say, the molten metal is forced through the nozzles Z and past suitable cheeks m^5 into the molds M. 35 The matrix-bars D are held in position during the casting of the types by the respective levers F. As the arms B return to position (shown at Fig. 1) the parts m^2 at once lower 40 and the cast types x^2 remain in the upper parts m' of molds M, owing to the presence in each of the molds of what is known as a "pin-hole" or "drag," and the types so remain until mechanically knocked out or delivered by a delivery-knife J, carried in a 45 slide j' at the back of the upper carrier A. This knife J is forced down by the same motion and at the same time as the levers E press against the upper parts of the matrix-bars D, so as to remove the matrices d^2 from 50 the types x^2 , and this action cuts off the tailings of the types x^2 and at the same time causes the said types x^2 to fall lengthwise onto a chute G—that is to say, as shown at Fig. 10. The lever 10 is coupled to a lever 15, ful- 55 crummed at 16, and the lever 15 is connected to the knife J by a rod 17. Therefore as the lever 10 lowers the rod 17 also lowers and causes the knife J to act in the manner described. 60 On the chute G are arranged a number of channels I, corresponding to the number of molds being used. The cast types fall therein in manner described, and they travel by grav-

ity onto a reciprocating table X, containing a number of bridge-shaped holders x' , the 65 types x^2 falling to positions between these holders, as shown at Figs. 5 and 6. The spaces between the holders x' form the termination of the channels I. When the types x^2 have so traveled by gravity onto the table X 70 and taken up positions between the holders x' , the table X is caused to move to the right, and the bridge-shape holders x' first pass over an inclined plate Y, onto which plate the types x^2 collect, and they are carried up this plate 75 by the sides of said holders and then onto a forked-shaped part y' of the incline Y, the holders x' finally passing between said forked-shape part and delivering the types close together and in line side by side, so that they 80 may be finally collected upon the type-founder's stick Q in a completed condition and ready for assortment. The table X is reciprocated in this manner at every operation of the machine by means of a connecting-rod z , 85 worked from an adjustable crank z' , carried on a driven shaft z^2 , worked from a pair of bevel-wheels z^3 and z^4 , driven from the shaft W.

Having fully described my invention herein, what I claim, and desire to secure by Letters Patent, is—

1. In a type-casting machine the combination of a number of molds arranged by fixing the upper part and one side of each mold to an upper carrier mounted on reciprocating 95 arms, and the lower part and opposite side of each said molds to a lower carrier supported on rods worked up and down obliquely by means of cams, said rods being supported on said cams and guided by oblique bearings at 100 upper parts substantially as described.

2. The combination in a type-casting machine of parts m' forming the upper part and one side of each mold, and parts m^2 forming the lower part and opposite side of each said mold, reciprocating arms B for moving the parts m' up to and away from nozzles Z and rods R with inclined or angular parts S, worked up and down obliquely by means of cams, the said rods R being supported on the 105 said cams and guided by oblique bearings at the upper parts, for closing the parts m^2 up to the parts m' when said parts are near the nozzle Z and moving the parts m^2 away at the same time as the parts m' are moved 110 away substantially as described.

3. In a type-casting machine the combination of molds so divided that the upper part and one side forms the top of mold, and the lower part and opposite side forms the bottom of mold, an upper carrier for supporting the said tops of molds, oscillatory arms for supporting said upper carrier, a lower carrier obliquely movable for supporting the bottoms of the molds, pivoted matrix-bars supported upon the upper carrier, levers and 120

tappets supported on said arms for closing and opening said matrix-bars, a knife mounted at the back of top of molds for cutting off the tailings and forcing the types from the 5 tops of molds substantially as described.

4. The combination in a type-casting machine of a chute, channels therein, sliding table with bridge-shaped holders, inclined plate with forked-shape formation for col-

lecting the cast type side by side in manner 10 substantially as described.

In witness whereof I have hereunto set my hand in the presence of two witnesses.

FRANCIS WILLIAM HEWS.
